COIN ACTUATED SWITCH

Mitchell A. Hall, Fort Thomas, Ky., assignor to
 Monarch Tool & Mfg. Company, Cincinnati,
 Ohio, a corporation of Ohio

Application September 6, 1938, Serial No. 228,520

1 Claim. (Cl. 194—9)

This invention relates to coin actuated switches for electrically operated apparatus such as automatic games, phonographs, vending machines, and the like. Such apparatus is equipped with 5 a coin receiving chute into which the patron inserts a coin to initiate the operation. The chute is provided with a pilot switch which is tripped by the coin momentarily to close an electric circuit controlling the operation of the apparatus. 10 After the control circuit has been energized by the coin, the operation of the apparatus is automatic and continues for a definite cycle at the end of which the circuits are automatically de-energized and the operation ceases.

15 The conventional coin chutes which have been employed in the past include protective devices which are effective to restrict the passage of coins other than those of proper denomination. These chutes include a magnetic deflector to 20 guide magnetically responsive slugs clear of the pilot switch. The switches are positioned relative to the discharge end of the chutes, and are adapted to be closed by the coins as they drop by gravity from the ends thereof. The switches, 25 themselves, are actuated by a lever which normally is in balanced repose. These levers are actuatable only by the impact of coins of predetermined weight upon them. Therefore, should an iron slug be inserted in a coin chute, it will be 30 deflected clear of the chute before the switch operating lever is reached, while a lighter, unauthorized coin or slug, even though it be the same in size as a proper coin, is not heavy enough to trip the switch to circuit closing 35 position.

The switches, of course, are small in size and naturally are of delicate construction in order to provide the necessary sensitivity. The operation of the switch is positive when the proper 40 coin is used. However, the switches may be intentionally tripped by the player by jolting or tilting the machine, for the purpose of closing the circuit without inserting a coin in the chute.

It has been one objective of the present inventor to provide a switch structure responsive 45 only upon the deposit of a proper coin in the receiving chute, which is effective to defeat improper operation of the machine, whether the machine be jarred, tilted, shaken, or vibrated 50 either intentionally or otherwise.

Another objective has been to provide a switch equipped with a protective holding device, which prevents actuation of the switch by jarring, but 55 which does not interfere with the normal sensitivity of the switch. Moreover, it has been a

further object to provide a sensitive switch which is more reliable and durable than those employed in the past. In this respect, the invention contemplates an improvement to facilitate the prompt response of the machine when a proper coin is inserted. In other words, therefore, the objective has been to prevent fraudulent operation of the machine when no coin is inserted, or to insure positive and prompt operation of the machine when a proper coin is applied to it. 10

Briefly, the present invention is predicated upon the employment of a switch in which a pair of movable contacts are employed for serial circuit closure. Magnetic means are provided for holding the contacts in open position against forces other than that imposed by a coin of sufficient weight delivered from the chute for serial closure of the contacts.

An embodiment of the holding device referred to may consist of a small permanent magnet positioned adjacent to the contact arms of the switch. The switch contact arms are of iron or steel and act as an armature or keeper for the magnet. In normal switch open position, the contact arms are magnetically held in open 20 position, and the switch, therefore, is not operable by jolts or jars. The contact arms of the switch are provided with an extended lever, at the outer end of which is fixed a coin-receiving 25 tongue or plate. This tongue is disposed just below the discharge end of the coin chute, so that coins roll onto the plate and thus trip the switch. The weight of the descending coin upon the plate is sufficient to break the magnetic holding 30 force exerted upon the switch arms. 35

The stationary contacts of the switch are located a considerable distance above the movable contacts, so that a very definite degree of movement is required before the contacts actually close when the switch lever is tripped. The active 40 field of the permanent magnet extends only a fraction of the total distance of the switch closing throw, preferably not more than one quarter of the total.

The switch lever may include some return 45 means, such as a balance spring tending to return the lever to switch open position, and includes adjustment means for causing the switch to close when a predetermined pressure is applied thereto. After the magnetic holding force has been 50 initially broken, there is no interference with the normal sensitivity of the switch. For this reason, the initial tripping movement of the switch will be accomplished regardless of the 55 weight of the coin, while actual switch closing

movement is governed by the spring in the normal manner. The holding device performs a function distinct from that of the spring.

The present improvement has made it possible 5 to use a shorter throw for the switch by dividing the total gap between two sets of contacts. This is accomplished by the use of a pair of contacts arranged in series in a control line providing a double break and thereby splitting the gap into 10 two parts. Thus the aggregate gap is sufficient to prevent arcing but the throw of the switch is greatly reduced. Additionally, this makes it possible to make the switch more compact.

Referring to the accompanying drawing illustrating 15 a preferred embodiment of the invention:

Figure 1 is a general view of the top portion of a vending machine illustrating the coin chute and switch installed thereon.

Figure 2 is an enlarged front view of a coin 20 chute with the improved switch mounted in operating relationship with the discharge end of the chute.

Figure 3 is a sectional view taken on line 3—3, Figure 2.

Figure 4 is a fragmentary rear view of a portion 25 of the coin chute illustrating the mounting of the switch.

Figure 5 is a side view of the switch with one of the casing sections removed to illustrate the relationship between the magnet and the switch 30 arms.

Figure 6 is a view similar to Figure 5, but with the intermediate plate removed, showing the trip lever in depressed position and the switch contacts in circuit closing engagement.

Figure 7 is a sectional view taken on line 7—7, Figure 5, further detailing the switch structure.

The present improvements are primarily directed to the pilot switch. For this reason, the mechanisms and circuits controlled by the switch 40 have been omitted and the disclosure confined to the switch and the coin chute with which it operates. Referring to Figure 1 of the drawing, the coin chute and switch assembly, indicated generally at 1, are shown installed in the upper portion 45 of a conventional coin-actuated vending device 2.

The coin-receiving chute terminates at the top in a projecting guide 3 having flanges 4 to form an open coin guideway leading into the chute. 50 The coin is placed in this guide and permitted to drop into a slot at the top of the coin chute. The coin chute is fabricated of two plates 5 and 6 held in spaced relationship upon a pair of spacers 7 and 8. These spacers are configurated 55 to define a curved passageway 9, which serves to check the descent of the coins as they descend through the chute.

The lower edge of the back plate 6 of the coin 60 chute is bent outwardly and upwardly to form a channel 10, defined by a vertical flange 11 and a bottom or web 12. This channel 10 is disposed at an angle to the horizontal to cause the coins to roll toward the switch as they drop from the open 65 lower end of the arcuate passageway 9. For this purpose the channel inclines downwardly from the passageway 9 and terminates just above the trip lever 13 of the switch 14. Because of the curvature of the passageway, the coins are guided 70 toward the upper end of the channel and therefore slow down considerably before rolling to the discharge end of the channel. This arrangement minimizes the effect of inertia and permits greater accuracy in governing the actuation of the switch.

For the purpose of directing and separating 75

iron slugs from the coin chute, the side plate 5 adjacent to the channel 10 is flared laterally at an angle in the area opposite the channel, as at 15, (Figure 3). The lower edge of the flared plate 5 is spaced away from the vertical flange 11 a sufficient distance to permit the passage therebetween of slugs which are attracted to the flared side plate by a permanent horseshoe magnet 16. This magnet is secured to the outer side of the plate 5 by means of a screw 17 and a washer 18. When 10 a magnetically attractive slug passes through the chute, it is deflected laterally by the magnet as it leaves the lower end of the passageway and follows the deflector plate, thus clearing the channel and dropping from the lower edge of the flared 15 deflector plate. In this manner unauthorized slugs are prevented from entering the channel and actuating the switch.

The switch 14 is mounted at the lower left-hand side of the coin chute upon a bracket plate 20 19 secured to the chute by screws 19a (Figure 4). The switch constitutes a rectangular body or housing 20 of dielectric material or insulation, such as hard rubber or the like, secured to the bracket plate by means of screws 21. A rock 25 shaft 22 is pivoted in the opposite side walls of the housing. Upon one end of this rock shaft is secured the trip lever 13, which projects horizontally and includes at the outer end a contact tongue 23 disposed just below the discharge end 30 of the coin chute. This trip lever normally is poised in a horizontal plane, as shown in Figure 2, in which position the switch contacts are open.

In the present embodiment of the invention, the trip lever is formed of light gauge wire and 35 configurated to include an upwardly projected finger 24. An adjustable tension spring 25 (Figure 4) is connected to this finger. The portion of the trip lever at the juncture of the finger 24 encircles the rock shaft and is secured thereto 40 between a pair of nuts 26 (Figure 3) screwed on the outer end of the rock shaft. The spring 25 serves to return the trip lever 13 to normal position after it has been tripped to circuit closing 45 position by the passage of a coin.

For the purpose of causing the switch to trip to circuit closing position upon predetermined contact pressure, an adjustment device is provided for governing tension of the spring 25. The adjustment device comprises a screw 27 loosely traversing a sleeve 28 formed at the lower edge of the bracket plate. A notch 29 is formed in the lower edge of the bracket plate at the inner end of the sleeve. An adjustment nut 30 is screw-threaded upon the screw 27 and confines the 50 screw against longitudinal movement. Rotation of this nut moves the screw longitudinally. The head of this screw includes an upwardly extended finger 31, upon which the opposite end of the 55 spring is engaged. This finger not only provides an anchorage for the spring, but serves also to prevent rotation of the screw, since the finger lies adjacent to the wall surface of the coin chute.

In this manner the spring may be adjusted to the proper tension to provide for actuation of the 60 lever upon a predetermined pressure of contact, the trip lever acting in the capacity of a scale to weigh the coin. If the weight is insufficient, the lever will not be tripped a sufficient distance to close the switch contacts.

Referring to Figures 5 and 6 of the drawing, it 70 will be observed that conductor arms 32 are provided and are adapted to carry the switch contacts 33. These contacts 33 are in contact with a permanent horseshoe magnet 34 of small size 75

located within the switch housing. The switch arms are in one piece, being the arms of a U-shaped piece, and constitute an armature for the magnet, each arm being in magnetic relationship with one pole of the magnet. The arms in one position serve to restrain closing movement of the switch by contact with the magnet and in the other as the bridge for the spaced contacts of the switch. The switch arm unit is formed of iron or steel or of a magnetic alloy and cooperates with a pair of corresponding contacts 34 located within the switch housing above the magnet and within the arc of switch arm swing.

The contacts 34 each are mounted upon a thin flat spring 35, each being in electrical contact with a respective control wire 36, which wires operate the vending apparatus. When the trip lever is actuated, the rock shaft is rotated to swing the contacts 33 upwardly into contact with the stationary contacts 34. The control current then flows between the contacts 34, through the switch arm unit, to energize the control circuit. The movable contacts 33 of the U-shaped switch arm are mounted on the angular portions of the respective arms facing outwardly. The contacting faces of these contact elements are slightly convex to provide a wiping action as the contacts engage. It will be evident that the circuit will be incomplete unless both sets of contacts are engaged; therefore it is necessary that the coin be of sufficient weight to impart complete switch closing movement to the arms before the apparatus is operated. The closing of the switch contacts occurs momentarily and the lever is immediately thereafter returned to open position by the action of the tension spring.

The switch housing is fabricated of two casing sections, in order to facilitate assembly of the parts. These sections, indicated at 37 and 38, are separated by a plate or wall 39 (Figures 3 and 4). The switch arm unit is secured to the rock shaft. The shaft for this purpose has a hub 40 centrally thereof formed of hard rubber or other insulating material. The connecting portion of the U-shaped arm unit is embedded in this hub and, in this manner, insulated from the shaft. The switch-holding magnet 34 is clamped between the two sections of the housing in position for magnetically holding the arms in switch open position. The two sections of the housing are held in assembly by means of the screws

and nuts 21, which draw the sections together and thus firmly clamp the magnet in place.

By holding the switch arms in switch open position magnetically, as above disclosed, it will be evident that the switch can be swung to circuit closing position only by inserting a coin of sufficient weight in the slot. Although it might be possible to prevent unauthorized actuation of the switch by increasing the tension of the return spring, this would not be feasible, as it naturally would destroy the sensitivity of the switch and render it unfit for the delicate function which it performs. Therefore, by providing the switch with a separate holding means, the adjustable tension spring may be used for the express and sole service of controlling the action of the trip lever within a delicate range, i. e. so that coins of certain weight will close the switch. The switch may be adjusted exactly as desired without regard to the possibility that the switch might be jarred or jostled into circuit closing position, since a separate means provides the holding force.

It will be noted that the switch arms swing in a relatively long arc of travel. The holding force of the magnet is, of course, effective for only a short distance, and when the gap between the magnet and the switch arm exceeds this distance, the magnetic attraction becomes ineffective. Therefore after the hold is initially broken by the weight of a coin, the spring then comes into play to govern the swing of the trip lever, independently of the magnet. It will be understood that other means for balancing the trip lever can be substituted for the spring.

Having described my invention, I claim:

In a coin operated switch mechanism, a coin actuated trip lever, a rock shaft carrying said trip lever, movable contacts actuated by said rock shaft, an electrical circuit including stationary contacts adapted to be engaged by said movable contacts, a coin delivery guide including a portion having very little incline from the horizontal for rolling the coin onto the trip lever, balance means on said trip lever for determining the force necessary to trip the same, a magnet in said switch and, a keeper secured on said rock shaft, said keeper being normally in contact with the magnet to hold said rock shaft stationary and adapted to swing clear of the magnet upon engagement of a coin with the trip lever.

MITCHELL A. HALL.
